UNITED STATES PATENT OFFICE.

JAMES J. FINNEGAN AND CHARLES E. WEBSTER, OF BENWOOD, WEST VIRGINIA.

GAGE-COCK.

No. 880,786.

Specification of Letters Patent.

Patented March 3, 1908.

Application filed October 10, 1907. Serial No. 396,724.

To all whom it may concern:

Be it known that we, JAMES J. FINNEGAN and CHARLES E. WEBSTER, citizens of the United States of America, and residents of Benwood, county of Marshall, and State of West Virginia, have invented certain new and useful Improvements in Gage-Cocks, of which the following is a specification.

This invention relates to new and useful improvements in gage-cocks for steam engines or locomotives, and more particularly to an automatic device which admits of the removal of a gage-cock without a resultant exhaustion of the steam from the boiler; and it consists in the particular construction, arrangement and combination of parts which will hereinafter be fully described.

The object of the invention is to provide an extremely simple and inexpensive valve device adapted to be employed in connection with an ordinary gage-cock which admits of the operation or manipulation of the gage-cock as ordinarily while said gage-cock is in place, but which upon the removal of said gage-cock will automatically close the opening to the atmosphere and effectually prevent the exhaustion of steam from the boiler.

In describing the invention in detail, reference is herein had to the accompanying drawing, forming a part of this specification, in which—

Figure 1 is a side elevation of an ordinary gage-cock to which our invention is applied; Fig. 2 is an enlarged longitudinal sectional view of the invention with the gage-cock detached therefrom; Fig. 3 is an end view of the valve; and Fig. 4 is a longitudinal sectional view of the invention with the gage-cock seated therein, showing the latter holding the valve in its normal unseated position.

Referring to said drawing, in which like designating characters distinguish like parts throughout the several views—1 indicates a gage-cock of an ordinary type having the usual tapered threaded end 2 for fitting in place in the boiler, and 3 indicates the valve device constituting the present improvement, said valve device being adapted for mounting in the boiler in precisely the same manner as that in which the gage-cock has hitherto been mounted, and also being adapted for having said gage-cock mounted therein. Said valve device consists of a valve casing 4, a screw cap 5, and a spring-controlled valve 6. Said valve casing has a tapered exteriorly-threaded wall 7 for screwing into the

ordinary gage-cock opening or seat and is provided with a tapered threaded socket 8 for the reception of the end 2 of the gage-cock, and with a socket or valve-chamber 9 in the end thereof opposite to said socket 8, the valve casing 4 being interiorly threaded at the outer end of said chamber 9 for the reception of said screw cap 5. A centrally-apertured wall 10 separates the socket 8 and chamber 9, the central aperture 11 admitting of communication therebetween, and a tapered seat 12 is provided for the valve 6. Said valve has a longitudinal stem 13 which is projected through and is slidable in said screw cap 5. A coil-spring 14 embracing said stem is seated at one end against the rear face of the valve and at its other end against the inner face of the screw cap, normally holding said valve seated. In the walls of said valve casing 4 is provided one or more ports 15 which admit of the entrance of steam from the boiler to the chamber 9, which steam is admitted therefrom, when the valve 6 is unseated, to the gage-cock 1. The said valve is normally held unseated against the tension of the spring 14 by said gage-cock, the extreme end of which stands in bearing engaged with forwardly-directed prongs 16 carried by said valve, and consequently said gage-cock is allowed to perform its function in the usual way without hindrance of any kind. But, when the gage-cock is withdrawn, the spring effects the seating of the valve, thus effectually preventing the escape of steam from the boiler.

Having thus described our invention, what we claim as new, and desire to secure by Letters Patent, is—

1. In a device of the character described, the combination with a gage-cock, of a valve device threaded upon the tapered end of said gage-cock, said valve device consisting of a tapered exteriorly-threaded casing, having in its outer end a threaded socket in which the gage-cock is seated, and having a valve chamber in its opposite end, a closure for the end of said second socket, a centrally-apertured wall between said sockets, a spring-controlled valve in said chamber for closing the aperture in said wall, prongs carried by the face of said valve and projected through said aperture against the end of the gage-cock, which latter normally holds said valve unseated against the tension of the valve-controlling spring, and inlet-ports in said casing for admitting steam to said chamber.

2. In a device of the character described, the combination with a gage-cock, of a valve device threaded upon the tapered end of said gage-cock, said valve device consisting of a 5 tapered exteriorly-threaded casing having in its outer end a threaded socket in which the gage-cock is seated, and having a valve chamber in its opposite end, steam inlet-ports in the walls of said chamber, a valve 10 seat between said chamber and said socket, a spring-controlled valve in said chamber, and an element carried by said valve projected through into bearing engagement with said gage-cock.
- 15 3. In a device of the character described, a valve device comprising a casing adapted for mounting in the gage-cock opening of a boiler and having a threaded socket in its
- outer end for the reception of a gage-cock, a socket in the inner end of said casing, a closure for the last-mentioned socket, a valve seat intermediate said sockets, a spring-controlled valve in said last-mentioned socket, prongs carried by said valve and projected into the first-mentioned socket, said prongs 25 being adapted to be engaged by the end of the gage-cock for normally holding said valve unseated, and ports for admitting of a passage of steam into said last-mentioned socket.

In testimony whereof we affix our signatures in presence of two witnesses.

JAMES J. FINNEGAN.
CHARLES E. WEBSTER.
